Primary Examiner — Cynthia Ramirez*Assistant Examiner* — Michael Maharajh(74) *Attorney, Agent, or Firm* — Knobbe, Martens, Olson & Bear, LLP(57) **CLAIM**

The ornamental design for a clip for a rack, as shown and described.

DESCRIPTION

FIG. 1 is a front perspective view of clip for a rack, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the figures are for the purpose of illustrating portions of the clip for a rack and form no part of the claimed design.
